UNITED STATES PATENT OFFICE

91,540

DESIGN FOR A COASTER WAGON

Antonio Pasin, Chicago, Ill., assignor to Radio
Steel & Mfg. Co., Chicago, Ill., a corporation
of Illinois

Application December 8, 1933. Serial No. 49,993

Term of patent 14 years

To all whom it may concern:

Be it known that I, ANTONIO PASIN, a citizen of the United States, residing at Chicago, in the county of Cook and State of Illinois, have invented a new, original, and ornamental Design for a Coaster Wagon, of which the following is a specification, reference being had to the accompanying drawing forming a part thereof, in which

Figure 1 is a perspective view from the side showing the front portion of the body extending upwardly and rearwardly from the base or floor portion of the body and the upper edge of the body

as curving downwardly and rearwardly and merging into a horizontal line at the upper side edges of the body, the rear portion of the upper edges of the body sloping downwardly and rearwardly; and

Fig. 2 is a perspective view from the front and side showing more particularly the contour of the upper edge of the body.

I claim:

The ornamental design for a coaster wagon substantially as shown and described.

ANTONIO PASIN.
